US0D1031090S

(12) **United States Design Patent** (10) **Patent No.:** **US D1,031,090 S**
(45) **Date of Patent:** **** Jun. 11, 2024**

(54) **LADDER**

(71) Applicant: **Jiaxing Explorer Metal Products Co., Ltd.**, Zhejiang (CN)

(72) Inventor: **Tingli Cui**, Zhejiang (CN)

(73) Assignee: **Jiaxing Explorer Metal Products Co., Ltd.** (CN)

(**) Term: **15 Years**

(21) Appl. No.: **29/916,858**

(22) Filed: **Nov. 15, 2023**

(51) LOC (14) Cl. **25-04**

(52) U.S. Cl.

USPC **D25/64; D25/62**

(58) **Field of Classification Search**

(57) **CLAIM**

The ornamental design for a ladder, as shown and described.

DESCRIPTION

FIG. 1 is a front view of the ladder, with the ladder shown in a retracted and partially folded position, showing my new design;

FIG. 2 is a rear view thereof, with the ladder shown in a retracted and partially folded position;

FIG. 3 is a left side view thereof, with the ladder shown in a retracted and partially folded position;

FIG. 4 is a right side view thereof, with the ladder shown in a retracted and partially folded position;

FIG. 5 is a top view thereof, with the ladder shown in a retracted and partially folded position;

FIG. 6 is a bottom view thereof, with the ladder shown in a retracted and partially folded position;

FIG. 7 is a top and front perspective thereof, with the ladder shown in a retracted and partially folded position;

FIG. 8 is a bottom and rear perspective view thereof, with the ladder shown in a retracted and partially folded position;

FIG. 9 is a top and front perspective view thereof, with the ladder shown in a partially extended and partially folded position;

FIG. 10 is a bottom and rear perspective view thereof, with the ladder shown in a partially extended and partially folded position;

FIG. 11 is a top perspective view thereof, with the ladder shown in a fully extended and open position;

FIG. 12 is a bottom perspective view thereof, with the ladder shown in a fully extended and open position,

FIG. 13 is a rear perspective view thereof, with the ladder shown in a retracted, folded, and closed position; and,

FIG. 14 is a front perspective view thereof; with the ladder shown in a retracted, folded, and closed position.
